UNITED STATES PATENT OFFICE.

ROBERT FRON, OF KANSAS CITY, MISSOURI, ASSIGNOR TO JOHN T. COSGROVE, OF KANSAS CITY, MISSOURI.

TELEPHONE MUFFLER AND VOICE CONTROL.

Application filed January 28, 1926. Serial No. 34,355.

The invention generally relates to telephone attachments which have for their purpose to provide for more distinct and private transmission of telephonic conversations.

In its more detailed nature the invention seeks to provide a simple and inexpensively manufactured appliance which may be quickly and conveniently attached to a conventional telephone transmitter and which is designed to closely fit the face about the mouth of one talking over the telephone and to so receive the sound vibrations set up by the conversation carried on that the words spoken will be clearly and distinctly audible to one at the receiving end of the line but practically inaudible to one closely adjacent the transmitting end of the instrument. In addition to providing for the muffling of the sound vibrations to render them inaudible to persons present in the room from which the message is transmitted, and thus facilitating transmission of secret or private conversations, means is also provided whereby the volume of the sound transmitted may be adjusted to meet demands occasioned by each particular telephonic connection.

With the above and other objects in view that will hereinafter appear the invention further resides in the novel details of construction, combination and arrangement of parts, all of which will be first fully described, then be particularly pointed out in the appended claims, reference being had to the accompanying drawing, in which:—

Figure 1 is a central horizontal section of my improved muffler and control attachment, parts of a telephone transmitter being shown in dotted lines.

Figure 2 is a cross section taken on the line 2—2 on Figure 1.

In the drawing in which like numerals of reference indicate like parts in all of the figures, 1 represents the base, 2 the standard, 3 the transmitter head, and 4 the mouth piece of a conventional telephone transmitter. The parts thus far described are conventional and are illustrated merely to show the application of the invention and form no part thereof, per se.

In carrying out the principles of my invention I provide a cylindrical casing 5 open at its rear end and of a diameter slightly larger than the transmitter head 3, an abutment ring 6 being ring-and-flange-secured on the casing as at 7 and adapted to abut the front face of the transmitter head to position the attachment, and a plurality of set screws 8 which take through the ring-and-flange connections 7 to the rear of the ring 6 and engage the rear curved part of the transmitter head 3 to secure the device to position in the manner shown in Figure 1 of the drawing.

The front end of the casing 5 is closed by the wall 9 which has a central aperture 10 in which is secured the mouthpiece 11 shaped as at 12 to snugly fit the face about the mouth of a talker to direct all sound vibrations into the casing and prevent escape of any part thereof directly into the room.

A muffler cylinder 13 is flange-secured as at 14 between the ring 6 and the end of the casing 5 so as to be mounted within and in spaced relation to the wall of the casing 5. The cylinder 13 is perforated as at 15 to provide for communication between the chamber within and that surrounding the said cylinder, and the front wall 16 thereof is so spaced from the flange mounting, and the cylindrical wall so proportioned, that it freely cups over the mouthpiece 4 when the attachment is mounted as illustrated in Figure 1 of the drawing. It will also be observed that the central aperture of the ring 6 is sufficiently large to freely pass over the mouthpiece 4 when the device is being mounted.

The front wall 16 of the cylinder 13 is provided centrally with frusto-coniform depression 17 adapted, when the device is mounted for use, to extend back a distance into the mouthpiece 4 of the transmitting instrument.

The rear wall 18 of the depression 17 has sound vibration passages 19 formed therein and a control disk 20, similarly apertured as at 21, is rotatably mounted as at 22 upon the said rear wall 18 so that when the said disk is rotated the apertures or passages 19

and 21 will be brought into or out of register to control or cut off direct passage of sound vibrations into and through the mouthpiece 4 to the diaphragm in the transmitter head.

5 To provide for the necessary movement of the disk 20 it is provided with an eye 23 through which is inserted the crank end 24 of the rotatable control rod 25 which passes through the casing 5 as at 26, the extended 10 end being provided with a knurled head 27 to facilitate the making of the adjustments.

In use the mouth is placed close against the shaped edge 12 of the mouthpiece 11 and the conversation proceeded with. All 15 sound vibrations are effectively directed into the attachment and through the same into the mouthpiece of the telephone instrument. In this manner conversation may be carried on unheard by persons in the room 20 from which the message is being transmitted.

The voices of different people carry in varying degree and this, considered also with the variations in sense of hearing of 25 different individuals and the variations in telephonic connections made at various times, makes very desirable the use of the sound devices 18, 15, 18-27.

When the apertures 19 and 21 are in full 30 register the sound vibrations are permitted to pass, in full volume, directly into the transmitter head mouthpiece 4. By varying the degree of opening through the wall 18 and disk 20 the volume and direct passage 35 of the sound vibrations may be varied and when the passages are wholly closed the sound vibrations will be caused to take a tortuous passage around the cylinder 13, through its apertures 15 into the space surrounding the mouthpiece 4 and into the annular space surrounding the depressions 17 and thereby considerably muffled or deadened before reaching the diaphragm within 40 the transmitter head 3.

45 The casing 5 may be provided with one or more apertures 28 providing communication between the interior of the casing and atmosphere. Thus air is permitted to enter and be expelled through the aperture 50 or apertures so that respiration during telephone conversation is not interfered with and all back pressures prevented.

A sound deadening ring 29 of felt or 55 similar material may be interposed between the ring 6 and the transmitter head 3 if desired.

60 By the use of my improved attachment it is possible to transmit secret or private messages inaudible to persons in the room in which the messages are being transmitted, also, to so control the sound vibrations as 65 to attain a maximum of efficiency in transmitting the messages under varying conditions due to variations in volume of voice of the transmitting person, of the sense of

hearing of the receiving person, and in the telephonic connections made at the central exchange office.

From the foregoing description, taken in connection with the accompanying drawing, 70 it is thought that the novel details of construction, the manner of use, and the advantages of the invention will be readily apparent to those skilled in the art to which it relates. 75

What I claim is:

1. A device of the class described comprising a casing adapted to fit over the transmitter mouthpiece of a telephone instrument, a mouthpiece communicating into 80 the interior of the casing, a perforated baffle cylinder carried by the casing in spaced relation therein and surrounding the transmitter mouthpiece when the device is mounted for use, a front wall carried by the cylinder in spaced relation in advance of the transmitter mouthpiece when the device is mounted for use, said wall having a central depression adapted to project back into said transmitter mouthpiece a distance in spaced 85 relation. 90

2. A device of the class described comprising a casing adapted to fit over the transmitter mouthpiece of a telephone instrument, a mouthpiece communicating into the interior of the casing and shaped to fit the face about the mouth of a user, and variable means for controlling the passage 95 of sound vibrations through the casing into the transmitter mouthpiece of the telephone instrument over which the casing has been fitted, said means including an apertured wall carried by the casing and extended a distance back into the transmitter mouthpiece and an apertured disk movable relatively upon the said wall, and a rod extended outside the casing to one side of said second mentioned mouthpiece for effecting movement of said disk. 100

3. The combination with a telephone 110 transmitter head and its mouthpiece, of a casing adapted to snugly fit over said head, an abutment ring secured in the casing and adapted to abut said head, set screws threaded through the casing wall beyond the ring 115 and adapted to impinge said head to secure the casing to position, a cylinder secured to the ring in spaced relation inside the casing and adapted to surround said transmitter head mouthpiece and having its cylindrical 120 wall perforated, said cylinder having its front wall provided with a central depression adapted to extend into said transmitter head mouthpiece and having sound vibration admitting passages. 125

4. The combination with a telephone transmitter head and its mouthpiece, of a casing adapted to snugly fit over said head, an abutment ring secured in the casing and adapted to abut said head, set screws threaded 130

ed through the casing wall beyond the ring and adapted to impinge said head to secure the casing to position, a cylinder secured to the ring in spaced relation inside the casing and adapted to surround said transmitter head mouthpiece and having its cylindrical wall perforated, said cylinder having its front wall provided with a central

depression adapted to extend into said transmitter head mouthpiece and having sound vibration admitting passages, a perforated disk mounted on the rear wall of the depression, and means for moving the disk to control the passage of sound vibrations through the passages in said depression wall.

ROBERT FRON.
